(57) **CLAIM**

The ornamental design for chair arms, as shown and described.

DESCRIPTION

FIG. 1 is a first front and left side perspective view of chair arms showing my new design.

FIG. 2 is a second front and left side perspective view shown separated from broken line environment structure thereof; FIG. 3 is a front and right-side perspective view shown separated from broken line environment structure thereof; FIG. 4 is a top view shown separated from broken line environment structure thereof;

FIG. 5 is a front view shown separated from broken line environment structure thereof;

FIG. 6 is a left side view shown separated from broken line environment structure thereof; and,

FIG. 7 is a right-side view shown separated from broken line environment structure thereof.

The broken lines immediately adjacent the shaded areas represent the bounds of the claimed design while all other broken lines are directed to environment and are for illustrative purposes only; the broken lines form no part of the claimed design.
